CHILD'S ROCKING HORSE TOY OR SIMILAR ARTICLE

Leslie C. Peltier, Delphos, Ohio, assignor to The Delphos
Bending Company, Delphos, Ohio, a corporation of Ohio

Filed Dec. 30, 1960, Ser. No. 63,405

Term of patent 7 years

(Cl. D34—15)

Fig. 1

Fig. 3

Fig. 1 is a perspective view of a child's rocking horse toy or similar article showing my new design;
Fig. 2 is a top plan view; and
Fig. 3 is a front end elevational view thereof.

I claim:

The ornamental design for a child's rocking horse toy or similar article, substantially as shown.
